(57) **CLAIM**

The ornamental design for a spraying device for bottles, as shown and described.

DESCRIPTION

FIG. 1 is a perspective view of a spraying device for bottles, showing my new design from the front, left side and top; FIG. 2 is a perspective view thereof, from the front, right side and top;

FIG. 3 is a left side elevational view thereof, the right side view being a mirror image;

FIG. 4 is a front elevational view thereof;

FIG. 5 is a rear elevational view thereof; and,

FIG. 6 is a top plan view thereof.

The broken lines in the drawings are for illustrative purposes only and form no part of the claimed design.
